UNITED STATES PATENT OFFICE.

ALFRED A. ARNOLD, OF GALION, OHIO, ASSIGNOR TO THE GALION METALLIC VAULT COMPANY, OF GALION, OHIO.

METALLIC BURIAL-VAULT.

1,360,865.

Specification of Letters Patent. Patented Nov. 30, 1920.

Application filed April 29, 1920. Serial No. 377,672.

To all whom it may concern:

Be it known that I, ALFRED A. ARNOLD, a citizen of the United States, residing at Galion, in the county of Crawford and 5 State of Ohio, have invented certain new and useful Improvements in Metallic Burial-Vaults, of which the following is a specification.

This invention relates to a metallic vault 10 for caskets. The invention especially provides for a burial vault of iron, steel, copper or metal alloy which is particularly adapted for shipment in that it is so constructed that the ends and the door thereof 15 do not become jammed or sprung out of place in shipment as may be the case with the usual types of metallic burial vaults.

The invention also has as an object the provision of a vault end including a flange 20 or flanges at right angles to the plane of the vault end and secured in place by welding or the like.

In the drawings:

Figure 1 is a view in perspective of the 25 front half of a vault constructed according to the present invention, and

Fig. 1^a is a view in perspective of the rear half of a slightly different form of vault,

Fig. 2 is a longitudinal vertical section of the vault shown in Fig. 1,

Fig. 3 is a vertical fragmentary section of a modified construction,

Fig. 4 is a vertical fragmentary section of 30 a modified construction,

Fig. 5 is a vertical fragmentary section of a modified construction,

Fig. 6 is a vertical fragmentary section of a modified construction of the rear end.

In detail the vault as shown in Figs. 1 40 to 3 inclusive comprises a substantially tubular body portion 1 which may be of any suitable form such, for instance, as practically rectangular in form but with flat 45 bottom and sides, the head or top portion being bulged as shown at 2 so that it will be set upright during shipment.

In producing the vault shown, a metal sheet is worked up into a tubular body of the 50 proper dimensions to form the vault, and the rear end 3, consisting of a metallic plate, is set in place within the end of the body, said plate being placed inwardly of the body

a sufficient amount to permit the edge of the body to be beaded down over the end 55 as shown at 4. However, previous to beading down the edge as shown at 4 the end 3 is secured in place by depositing, by oxy-acetylene or electric welding, a metallic fillet 5 at the juncture of the end 3 with the 60 body of the vault thus forming an integral seal and support for the end 3 after which the bead 4 is produced in any suitable manner, thus preventing displacement of the end either inwardly or outwardly of the 65 body 1.

Similarly, the front end or head comprises an angle iron 7 having the flange 8 set into the body 1 of the vault, as shown in Fig. 2, so that the edge of the vault may 70 be beaded therearound as shown at 9. However, previous to the beading the metallic fillet 10 is deposited by oxy-acetylene or electric welding to form an integral part of the angle iron 7 and body 1 in the same 75 manner as was done with the end 3. After this the beading 9 is produced in any suitable manner.

Mounted on hinges 11 secured to the side wall of the body 1 is a door 12 provided 80 with locking members 13 moved outwardly by a central member 14 operated by the spindle 15 whereby said members 13 may be caused to engage behind the angle iron 7 when the door 12 is closed. The door 12 is 85 of proper proportions to fit within the recess formed by the angle iron 7.

In the vault shown in Fig. 1^a the tubular body 1^a is formed of sheets bent to proper coöperating shape and riveted together as 90 shown. The ends are mounted in the same manner as described in connection with Figs. 1 and 2 and hence no description is necessary. However, in either form of the vault rivets may be used in connecting the 95 angle irons to the body 1 as well as the welded fillet.

The fragmentary view shown in Fig. 3 shows the angle iron 16 reversed in position from that shown in Fig. 2 and with the fillet 100 17 on the interior thereof in which case it is possible to omit the beading down of the edge of the tubular body, leaving a right angle joint on the exterior into which the door sheet fits thereby protecting the door 105 edges.

A particularly important feature of the invention is the fact that the flange 8 sets the door 12 inwardly of the end of the vault to such an extent that it cannot be damaged in any way during the handling of the vault.

It is, of course, recognized that the end 3 may be similarly set into the rear end of the vault by using a member similar to the angle iron 16 with a sheet of metal forming the 10 end closure.

In Fig. 4 is shown a T iron 18 which may be used equally as well as the angle iron, or a channel iron 19 may be used, in either case being held in place by the metal fillet 20 or 15 21, as the case may be.

The rear end may be formed of a sheet carrying a flange as indicated at 22 and provided with a metal fillet 23.

I claim:

20 1. A metal vault comprising a tubular body having its end edges beaded, an end fitting against the inner side of the bead, and a fillet in the angle defined by the body

and the inner face of the end and integrally united with the end and the body.

2. A metal vault comprising a tubular body having inset ends, welded fillets holding the ends in position against inward displacement, and beaded means retaining the ends against outward displacement and 30 forming a finished joint between said body and ends.

3. A metal vault comprising a body having an inset end, and a fillet integrally united with the body and the end and holding said end against displacement.

4. A metal vault comprising a tubular body, an inset head having a peripheral flange at right angles to the wall of the head, a metallic fillet deposited integrally 40 with the head and body on the inner side thereof, and a bead formed by peening the edge of the body on the edge of said flange.

In testimony whereof I affix my signature.

ALFRED A. ARNOLD. [L.S.]
